UNITED STATES PATENT OFFICE

GEORGE FRANK RUEHL, OF DETROIT, MICHIGAN

WINDOW

Application filed May 28, 1931. Serial No. 540,751.

This invention relates to certain new and useful improvements in windows, and the primary object of this invention is to improve upon that type of window which employs a sliding sash that is capable of also being swung inwardly or outwardly relative to the window frame on a horizontal pivot.

A very important object of this invention is to provide improved rails for the sliding sash, together with improved means for connecting the window sash with its rails so as to be retained in a substantially vertical position when the window is to be raised or lowered in the usual manner, said means also including means for retaining the window at the desired angle relative to the vertical whereby the window may be used somewhat in the nature of a ventilator.

Other objects and advantages of the invention will become apparent from a study of the following description, taken in connection with the accompanying drawings wherein:

Figure 1 is a front elevational view of a window embodying the features of the present invention.

Figure 2 is a longitudinal sectional view therethrough.

Figure 3 is a sectional elevational view for more clearly illustrating the application of the invention to the window sash.

Figure 4 is a view similar to Figure 2 and showing the sash swung to a horizontal position.

Figure 5 is a fragmentary detail sectional elevational view taken substantially on the line 5—5 of Figure 1.

Figure 6 is an elevational view of a locking device for retaining the sash in a substantially vertical position.

Figures 7 and 8 are detail sectional views taken substantially on the lines 7—7 and 8—8 respectively of Figure 4.

Figure 9 is a vertical sectional view through the locking device, the same being shown as applied to the window sash.

Figure 10 is a perspective view of a sash cord guide plate.

With reference more in detail to the draw-

ings, it will be seen that F designates generally a conventional window frame having the sliding sashes S operable therein. Each of the side members 11 of the frame F is provided with the usual outer window stop 12 and the intermediate window stop 13.

According to the present invention there is provided for each sash S, and associated with each side member 14 of the window sash a guide rail comprising a pair of telescoping sections 15 and 16 substantially channel shaped in cross section. The sections 15 and 16 are normally urged outwardly from one another through the medium of suitable spring devices 17. The section 16 of the guide rail slidably fits between the stops 12 and 13, and the section 15 is normally urged outwardly by the spring devices 17 into engagement with an adjacent face of an adjacent side sash member 14. (See Figure 8.)

The channel shaped section 16 has one side thereof provided with an extension 18 coplanar therewith and merging at its free edge into an inwardly directed longitudinally extending spring catch or lip 19 receivable in a longitudinal groove 20 provided on the outer face of the sash member 14 and yieldably engageable with one edge of a keeper plate 21 provided on said outer face of the sash member 14 adjacent the groove 19 whereby provision is made for retaining the window sash S in a vertical position.

The extension 18 at its lower end is hingedly connected to the lower sash member 14a as at 22 so that, as is apparent from a study of Figure 4, by pulling inwardly on the window sash S, the keeper plate 21 will be moved out of engagement with the latch member 19 and the hinge 22 provides a horizontal pivot for the sash. For retaining the sash at the desired angle to the vertical when swung inwardly as just explained, each side member 14 of the sash has pivotally connected thereto one end of a link 23, the free end of which link is provided with a pin operable in a longitudinal slot 24 provided on the rail section 15 and engageable with a selective one of a series of vertically spaced notches 25 provided on said rail section 15.

As is thought apparent, the sectional guide

rail constructed in accordance with the present invention serves to guide the window sash during the raising and lowering thereof.

Each of the said rails is also connected to 5 one end of the usual sash cord therein designated by the reference character 26. Said one end of the sash cord 26 extends downwardly between the sections 15 and 16 through an aperture in a guide plate 27 suitably mounted 10 between the rail sections 15 and 16 and the free end of the cord is suitably notched so as to engage the under face of the plate 27 as suggested in Figures 2 to 4 inclusive.

As clearly shown in Figure 3, the guide 15 rails extend upwardly from the lower end of the sash side members 14 and terminate at their upper ends in downward spaced relation with the top of the sash. Each sash member 14 at its upper end is provided with an additional locking device designated generally by the reference character 28, which additional locking device serves to prevent forcing the window inwardly about its hinge or pivots 22 by one on the outer side of the window. 20 As for example by one attempting unauthorized entrance into the house or room.

Each of the locking devices 28 comprises a substantially U-shaped plate or body member 29 provided between the sides 30 thereof 30 with a vertical rib 31 channel shaped in cross section and at its lower end projects beyond the corresponding end of the plate 29. At its lower end, the rib 31 is hinged to a plate 32 that is suitably secured to the sash member 35 14 above the guide rail associated with said sash member. The rib 31 has also anchored thereto one end of a longitudinally bowed leaf spring 33 accommodated within a vertical groove 34 provided in the sash member 14. 40 The spring 33 being normally expanded, will force the plate 29 into the space between the window stops 12 and 13. The outer side member 30 of the plate 29 is accommodated in a vertical groove 35 provided in the sash member 14 while the inner side member 30' of plate 29 engages the inner face of the sash member 14 so that the sash member 14 as it were is confined between the sides 30 and 30' 45 with the result that when the plate 29 is arranged between window stops 12 and 13 the window sash is locked against being swung inwardly by one on the outer side of the window.

The inner side member 30' of the locking 55 plate 29 is provided with a suitable finger piece 36 to facilitate drawing the plate 29 inwardly toward the sash member 14 against the action of spring 33 and from between the stops 12 and 13 whereby the window sash will 60 then be free to be swung about its hinges 22.

From the foregoing then it will be seen that I have provided efficient and practical means for slidably and pivotally supporting a window sash within the window frame, and for 65 locking the window sash against being swung

inwardly by an unauthorized person on the outer side of the window.

Although the foregoing is illustrative of a practical embodiment of the invention, it is to be understood that I do not desire to restrict myself to the herein described particular details of construction, nor to limit the invention other than is required by the prior art and the scope of the appended claims. 70

Having thus described my invention, what 75 I claim as new is:

1. In combination, a window frame, a window sash slidably and pivotally mounted therein, a member slidable between adjacent window stops of said frame, means operatively connecting said member with said sash whereby provision is made for guiding the sash during sliding movement thereof, said means including hinge means connecting said member with the sash whereby said member may be swung inwardly toward the sash from between said window stops whereby the sash will be free for swinging movement relative to the frame, and yieldable means for normally urging said member into position between said window stops. 80

2. In combination a window frame, a window operable therein, means for mounting said sash in said frame for sliding movement relative to the frame and also swinging movement relative to the frame, said means comprising in combination with the window stops of the frame, a lower guide rail operable between said stops and an upper combined guide and locking device slidable between said window stops, means for hingedly connecting the window sash with said rail to permit swinging movement of the sash and means carried by said locking device and co-operable with said sash whereby said locking device may be moved laterally inwardly toward the sash out of engagement with said window stops to permit swinging movement of the sash, said locking device being provided with means whereby the latter may be moved relative to said sash from one side only of the window. 95

3. In combination a window frame, a window operable therein, means for mounting said sash in said frame for sliding movement relative to the frame and also swinging movement relative to the frame, said means comprising in combination with the window stops of the frame, a lower guide rail operable between said stops and an upper combined guide and locking device slidable between said window stops, means for hingedly connecting the window sash with said rail to permit swinging movement of the sash and means carried by said locking device and co-operable with said sash whereby said locking device may be moved laterally inwardly toward the sash out of engagement with said window stops to permit swinging movement of the sash, said locking 100 device being provided with means whereby the latter may be moved relative to said sash from one side only of the window. 105

device being provided with means whereby the latter may be moved relative to said sash from one side only of the window, and said rail and window sash provided with cooperating means for yieldably retaining the window sash in vertical position independently of said locking device.

4. In combination a window frame, a window operable therein, means for mounting said sash in said frame for sliding movement relative to the frame and also swinging movement relative to the frame, said means comprising in combination with the window stops of the frame, a lower guide rail operable between said stops and an upper combined guide and locking device slidable between said window stops, means for hingedly connecting the window sash with said rail to permit swinging movement of the sash and means carried by said locking device and cooperable with said sash whereby said locking device may be moved laterally inwardly toward the sash out of engagement with said window stops to permit swinging movement of the sash, said locking device being provided with means whereby the latter may be moved relative to said sash from one side only of the window, and said rail and window sash provided with cooperating means for yieldably retaining the window sash in vertical position independently of said locking device, and said last mentioned means providing means for limiting swinging movement of the sash from a substantially horizontal to a vertical position.

5. In combination a window frame, a window operable therein, means for mounting said sash in said frame for vertical sliding movement relative to the frame and also vertical swinging movement relative to the frame, said means comprising in combination with the window stops of the frame, a lower guide rail operable between said stops and an upper combined guide and locking device slidable between said window stops, means for hingedly connecting the window sash with said rail to permit swinging movement of the sash and means carried by said locking device and cooperable with said sash whereby said locking device may be moved laterally inwardly toward the sash out of engagement with said window stops to permit vertical swinging movement of the sash, said locking device being provided with means whereby the latter may be moved relative to said sash from one side only of the window, and said rail and window sash provided with cooperating means for yieldably retaining the window sash in vertical position independently of said locking device, and said last mentioned means providing means for limiting swinging movement of the sash from a substantially horizontal to a vertical position, and means for securing the sash at the desired angle relative to the perpendicular.

6. In combination a window frame, a window operable therein, means for mounting said sash in said frame for vertical sliding movement relative to the frame and also vertical swinging movement relative to the frame, said means comprising in combination with the window stops of the frame, a lower guide rail operable between said stops and an upper combined guide and locking device slidable between said window stops, means for hingedly connecting the window sash with said rail to permit swinging movement of the sash and means carried by said locking device and cooperable with said sash whereby said locking device may be moved laterally inwardly toward the sash out of engagement with said window stops to permit vertical swinging movement of the sash, said locking device being provided with means whereby the latter may be moved relative to said sash from one side only of the window, and said rail and window sash provided with cooperating means for yieldably retaining the window sash in vertical position independently of said locking device, and said last mentioned means providing means for limiting swinging movement of the sash from a substantially horizontal to a vertical position, and means for securing the sash at the desired angle relative to the perpendicular, 95

In testimony whereof I affix my signature. 100
GEORGE FRANK RUEHL.
